UNITED STATES PATENT OFFICE.

SAMUEL HASLAM, OF ATTLEBORO, MASSACHUSETTS.

VANITY-CASE.

1,354,970.

Specification of Letters Patent.

Patented Oct. 5, 1920.

Application filed March 29, 1920. Serial No. 369,722.

To all whom it may concern:

Be it known that I, SAMUEL HASLAM, a citizen of the United States, and a resident of Attleboro, in the county of Bristol and State of Massachusetts, have invented a new and Improved Vanity Case, of which the following is a full, clear, and exact description.

This invention relates to improvements in vanity cases, an object of the invention being to provide an improved construction of receptacle having a pair of compartments therein, the partition dividing the compartments being secured in the receptacle and providing a hinged support for the receptacle cover.

A further object is to provide a vanity case in which the partition dividing the receptacle into compartments operates to support or connect the hinged cover and also supports a catch which engages the cover to hold the latter in closed position.

A further object is to provide a vanity case of extremely simple, inexpensive construction, attractive in appearance and strong and durable in use.

With these and other objects in view the invention consists in certain novel features of construction, and combinations and arrangements of parts, as will be more fully hereinafter described and pointed out in the claims.

In the accompanying drawings—

Figure 1 is a plan view showing my improved vanity case with the cover in open position;

Fig. 2 is a perspective view of the partition member 2; and

Fig. 3 is a view in transverse section through the center of the vanity case with the cover in closed position.

1 represents the body or casing of my improved vanity case which is of general elliptical form constituting a receptacle divided by my improved partition 2 into two circular compartments 3 and 4.

My improved partition member 2 has an upper horizontal wall 5 and curved walls 6 at the edges thereof concentric with the curved ends of the casing or receptacle 1. The partition member 2 is of a length to fit snugly the transverse dimension of the receptacle and is secured in the receptacle by means of solder or other securing means.

55 The partition member 2 at one end at its

upper edge is made with a series of alined sleeves 7 adapted to receive between them similar sleeves 8 fixed to one edge of the receptacle cover 9, and a hinge pin 10 is located in the alined sleeves 7 and 8 to hingedly connect the cover to the receptacle. A spring tongue 11 is secured by solder or other securing means to the inner face of one of the curved walls 6 and at its outer end, as shown at 12, is bent at an angle and extends substantially parallel to the outer wall of the receptacle 1.

A beveled lug 13 is provided on an upward extension 14 of the portion 12 of tongue 11 at the free end of said portion 12, and the upper wall of the partition 2 is made with a recess 21 to permit the necessary movement of the tongue. This lug 13 is adapted to engage in a recess 15 in the front wall of the cover 9 to lock the cover in closed position. A forwardly projecting lug 16 is provided on the forward portion 12 of the tongue 11 and extends through a slot 17 in the front wall of the receptacle 1.

The tongue 11 and the parts carried thereby constitute a spring catch so that when the cover 9 is closed and forced into closed position, the catch will spring into locked engagement with the cover as the lug 13 will spring into the notch or recess 15. The lug 16 which projects through the receptacle can be pressed inwardly to release the catch from its holding position and permit the cover to be opened.

The receptacle 1 at its upper edge is made with an inwardly offset portion 18 which forms an upwardly projecting flange 19 to fit snugly within the cover 9 and also provides a ledge 20 which acts as a stop for the downward movement of the cover, and hence, when the cover is closed, it will snugly fit the receptacle and form a tight closure therefor.

Various slight changes might be made in the general form and arrangement of parts described without departing from the invention, and hence I do not limit myself to the precise details set forth, but consider myself at liberty to make such changes and alterations as fairly fall within the spirit and scope of the appended claims.

I claim:

1. A vanity case, comprising a receptacle, a partition in the receptacle dividing the latter into two compartments, a cover hinged

to the partition and adapted to close the receptacle, and a catch on the partition adapted to lock the cover in closed position.

2. A vanity case, comprising a receptacle, 5 a partition member in the receptacle having curved walls at opposite sides thereof substantially concentric with the ends of the receptacle, a cover hinged to one end of the partition member, a spring catch connected 10 to the other end of the partition member, said cover having a notch therein adapted to receive the spring catch, and a catch operating lug secured to said catch and projecting through the receptacle.
- 15 3. A vanity case, comprising a receptacle, a partition member in the receptacle having

curved walls at opposite sides thereof substantially concentric with the ends of the receptacle, a cover hinged to one end of the partition member, a spring catch connected 20 to the other end of the partition member, said cover having a notch therein adapted to receive the spring catch, and a catch operating lug secured to said catch and projecting through the receptacle, said 25 receptacle having an inwardly offset upper edge forming an upwardly projecting flange and a laterally extending shoulder, said flange adapted to fit within the cover, and said shoulder adapted to limit the closing 30 movement of the cover.

SAMUEL HASLAM
